STORAGE CABINET FOR GAS CYLINDERS

Melvin E. Price, Warsaw, Ind., assignor to Price's Gas
Equipment, Inc., Columbia City, Ind.

Filed Apr. 27, 1972, Ser. No. 248,346

Term of patent 7 years

Int. Cl. D6—04

U.S. Cl. D6—186

Fig. 1

Fig. 2

Fig. 3

Fig. 4

Fig. 5

FIG. 1 is a perspective view of a storage cabinet for gas cylinders embodying the applicant's design;

FIG. 2 is a front elevational view of the cabinet shown in FIG. 1;

FIG. 3 is an elevational view of the cabinet shown in FIG. 1;

FIG. 4 is a top plan view of the cabinet shown in the preceding figures; and

FIG. 5 is a rear elevational view of the cabinet.

I claim:

The ornamental design for a storage cabinet for gas cylinders, substantially as shown.
